UNITED STATES PATENT OFFICE.

JAMES A. MURRAY, OF NEW HAVEN, CONNECTICUT, ASSIGNOR TO THE SEAMLESS RUBBER CO., OF NEW HAVEN, CONNECTICUT, A CORPORATION.

DESIGN FOR A RUBBER BATHING-CAP.

46,603.

Specification for Design.

Patented Oct. 27, 1914.

Application filed March 16, 1914. Serial No. 825,183. Term of patent 7 years.

To all whom it may concern:

Be it known that I, JAMES A. MURRAY, a citizen of the United States, residing at New Haven, in the county of New Haven and State of Connecticut, have invented a new, original, and ornamental Design for a Rubber Bathing-Cap, of which the following is a specification, reference being had to the accompanying drawing, forming part thereof.

The figure is a perspective view of a rubber bathing cap, showing my new design.

I claim:

The ornamental design for a rubber bathing cap, as shown.

JAMES A. MURRAY.
